METHOD OF AND APPARATUS FOR
OPERATING HOT CATHODE LAMPSBurghardt P. Rupersburg, St. Clair Shores, Mich.,
assignor, by mesne assignments, to Syncro De-
vices, Inc., Detroit, Mich., a corporation of
Michigan

Application July 31, 1944, Serial No. 547,329

5 Claims. (Cl. 315—96)

1

The invention relates to an improved circuit for operating hot cathode, gas or vapor lamps.

In the present state of the art, hot cathode lamps in commercial operation require the use of a separate transformer and also thermostatically operated switches connected into the circuit between the transformer and lamps. These elements not only add to the cost of the original installation, but also introduce certain maintenance problems because of the mechanically operating parts.

It is an object of the present invention to provide a circuit control for hot cathode lamps which is entirely electrical and free from mechanically operated parts.

Another object is to provide a circuit for hot cathode lamps which obtains instant starting and uniform operation when the lamps are connected to ordinary commercial power lines such as 120 volts, 60 cycle A. C.

These and other objects are attained by providing the apparatus hereinafter more fully described and illustrated in the accompanying drawings, wherein

Figure 1 is a circuit diagram illustrating my invention as applied for operating a pair of hot cathode lamps;

Figure 2 is a circuit diagram illustrating the invention as applied for operating a single hot cathode lamp.

In the drawings, A represents a commercial type of hot cathode gas discharge lamp comprising an elongated transparent tube B filled with suitable gases or vapors in the known manner and having cathodes D¹ and D² at opposite ends thereof. These cathodes are in the form of filaments each connected to two terminals F₁, F₂, F₃ and F₄ respectively. The cathodes are usually connected to the protective horns G₁ and G₂ in the known manner.

Referring now to the circuit for the single lamp illustrated in Figure 2, the terminal F₁ is connected to one side of the line through capacitance C₁ and inductance L₁. The terminal F₃ at the opposite end of the lamp is connected to the opposite side of the line. Terminals F₂ and F₄ are connected together through the inductance L₂. The values for L₁ and C₁ are so selected as to be resonant at line frequency. The values of L₂ and C₁ must be partially resonant, sufficient to start the lamp in operation. Although not absolutely essential, it is preferable to place a small capacitance C₃ across the line between L₁ and C₁ which has the effect of increasing the ease of starting.

In Figure 1 a second lamp A₁ having terminals 55

2

T₁, T₂, T₃ and T₄ is connected to the circuit of Figure 1 in the following manner. Terminal T₁ is connected through capacitance C₂ to the line between L₁ and C₁. Terminal T₃ is connected to the other side of the line. Terminals T₂ and T₄ are connected together through inductance L₂.

The values of the inductances and capacitances are predetermined to obtain the effect heretofore mentioned, namely, that L₁ and C₁ are near resonance at line frequency and L₂ and C₁ are partially resonant sufficient to strike. Without limitation, and merely by way of example, the following values for inductances and capacitances are given for the circuit of Figure 2 when operating on a 60 cycle circuit.

L₁ 0.78 henrys, 20 ohms, 900 turns #26 American Wire Gauge, enameled copper magnet wire on an EI #11 core, square stack. Butt joint assembly. Air gap 0.15 to .020.

20 L₂ and L₃ 19.0 henrys, 65 ohms D. C., 1200 turns #30 American Wire Gauge, enameled copper magnet wire on an EI #625 core, square stack. 100% interleaved.

C₁ and C₂ 4.0 to 4.75 microfarads.

25 The values for inductances and capacitances for the circuit of Figure 1 when operating on a 60 cycle circuit are the same as those given above for the circuit of Figure 2 except that in Figure 1 L₁ is 1.50 henrys.

30 In each of the circuits of Figures 1 and 2 the principles of resonance enter into the operation, the wave forms are not distorted, nor are they exponential as one would expect from the use of large capacitances, nearly the opposite being true, resulting in increased lamp life, instant starting, even at low temperatures.

35 The absence of mechanical or thermal action insures long life, decreased maintenance, and higher efficiency power transfer of this type of lamp auxiliary.

40 In explanation of operation of this type of circuit, L₁ and C₁ in Figure 2 are so adjusted that they are near resonance at line frequency. This allows nearly the full line voltage to appear at the lamp terminals, but a limited current flow which is primarily determined by the value of capacitance C₁.

45 The energy appearing on the lamp side of C₁ must pass through the inductance L₂ which is so adjusted that it creates a slight rise in voltage acting in conjunction with C₁. This rise in voltage plus the increased cathode temperature, which is due to the passage of current through the cathode, causes the lamp to strike a discharge. Immediately the lamp discharges, it

destroys the greater part of the resonant effect between L_2 and C_1 allowing the lamp to pass the controlled current from the L_1-C_1 combination, the inductance L_2 in effect dropping out of circuit due to its high impedance in relation to the negative resistance characteristics of discharge lamps L_2 being a load controlled inductance immediately on slight reductions of line voltage cuts in the circuit to maintain the correct voltage for lamp operation, at the same time starting a current flowing through the lamp filaments raising their temperature, which allows the lamp to remain operating even at great reductions in the line voltage. When the line voltage resumes its normal value, L_2 again drops out of circuit and the current ceases to flow through the filaments allowing the lamp to again function normally.

What I claim as my invention is:

1. A circuit for operating a plurality of hot cathode discharge lamps each of the type comprising a vitreous tube having two terminals at each end thereof and a cathode resistance within each end of the tube connected between the terminals at the respective ends of the tube, said circuit comprising an inductance and a capacitance connected in series with one of the terminals at each end of one of said tubes and a parallel connection connecting said inductance in series with a second capacitance and one of the terminals at each end of a second tube, the other terminals of each of said lamps being connected to a separate inductance for each lamp.

2. A circuit for a hot cathode discharge lamp comprising a source of alternating current of predetermined frequency, a conductor between one side of said source and one end of a cathode resistance, a conductor between the other side of said source and one end of a second cathode resistance at the opposite end of said lamp thus completing a circuit through said lamp when the gas therein is ionized, an inductance and a capacitance in series in said circuit through said lamp having values such as to provide substantial resonance at said predetermined frequency, and a second inductance connected between the other ends of said cathode resistances having a value such as to energize said cathodes sufficiently to ionize said gas to the striking point and to pass a substantial current through said lamp, said second inductance having a substantially greater impedance than said first inductance.

3. A method of starting and maintaining a hot cathode discharge lamp without mechanically moving parts which comprises connecting said lamp to an alternating current supply in series with an inductance and a capacitance and providing a second inductance of substantially greater impedance than said first inductance in a shunt circuit around said lamp including the cathode resistances in series with said second inductance.

4. The method of starting and maintaining a hot cathode discharge lamp which comprises passing an alternating current through an inductance and a capacitance in substantial resonance with the frequency, passing said current through the cathode resistances of said lamp and through a second inductance shunted around said lamp and having such value as to cause the lamp to strike and to thereafter pass the current between the cathodes of said lamp, said second inductance having a substantially greater impedance than said first inductance.

5. The combination with a hot cathode discharge lamp having cathode resistances at opposite ends thereof, of a source of alternating current supply of approximately 120 volts and 60 cycles, an inductance and a capacitance connected in series between said alternating current supply and said lamp, said inductance having an impedance on the order of 1.0 henry and said capacitance having a capacity on the order of 4 microfarads, and a second inductance having an impedance on the order of 19.0 henrys connected between said opposite cathode resistances and in series therewith, and in parallel with said lamp during both starting and operation of said lamp.
